UNITED STATES PATENT OFFICE.

NAJEEB NAJA, OF NEW YORK, N. Y.

DESIGN FOR AN EMBROIDERED COLLAR.

44,876.

Specification for Design.

Patented Nov. 11, 1913.

Application filed June 28, 1913. Serial No. 776,435. Term of patent 3½ years.

To all whom it may concern:

Be it known that I, NAJEEB NAJA, a citizen of Turkey, residing in the borough of Manhattan, city, county, and State of New York, have invented a new, original, and ornamental Design for an Embroidered Collar, of which the following is a specification, reference being had to the accompanying drawing, forming a part hereof.

The figure is a plan view of an embroidered collar showing my new design.

As shown in the drawing my design consists of two butterflies, one on either side of the pattern of embroidery, and an eagle

at the lower part thereof, with embroidery of conventional design in the general form of an inverted horseshoe.

I claim—

The ornamental design for an embroidered collar as shown and described.

In testimony whereof, I have signed my name to this specification in the presence of two subscribing witnesses.

NAJEEB NAJA.
